UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

MECHANISM FOR FEEDING STRIPS

Original application filed March 17, 1919, Serial No. 283,018. Divided and this application filed March 9, 1927. Serial No. 174,078.

This invention relates to mechanism for feeding strips, and the embodiment of the invention herein illustrated and described is designed particularly to feed to nail making machines the metal strips from which the nails are formed. The present application is a division of my copending application, Serial 283,018, filed March 17, 1919, upon which Letters Patent of the United States No. 1,651,452, were granted December 6, 1927, in which I have shown and claimed a new and improved controlling mechanism for controlling the operation of the mechanism which supplies new strips of material to the carrier.

Letters Patent of the United States, No. 1,396,191, granted November 8, 1921, on my co-pending application, Serial No. 169,562 discloses mechanism for feeding strips to a nail making machine comprising a carrier for presenting the strips to the machine including a nozzle and means controlled by a strip in the carrier for automatically supplying strips to the carrier. Mechanism is also disclosed therein for transferring the strips of material from a series of magazines, in each of which a strip is originally placed, to the carrier which presents the strips to the mechanism operating upon them; and the operation of the transferring mechanism is subject to a controlling mechanism which is governed by a feeler directly responsive to the presence or absence of a strip in the carrier, whereby a continuous supply of strips is assured for presentation to the operating mechanism with assurance against supplying them faster than needed and so jamming and possibly injuring the various mechanisms. When the controlling mechanism has effected an actuation of the supplying means, it is rendered inoperative to cause further actuation until reset by the introduction of a new strip into the carrier. The introduction of more than one strip at a time into the carrier is thus avoided, as well as useless repeated actuation of the supplying means, in case of an empty magazine. One of the objects of the present invention is to provide improved mechanism of the same general character as

that forming the subject-matter of said Letters Patent, No. 1,396,191.

In accordance with one feature of the present invention the mechanism for controlling the means for supplying strips to a rotary carrier, with which the machine is provided, is mounted upon a support with respect to which the carrier rotates. Regarded from another aspect this feature comprises an instrumentality which is movable with the supplying means for rendering inoperative the means for actuating the supplying means. Because of the fact that the means for rendering the actuating means inoperative is moved, the actuating means itself may be made substantially stationary. An advantage resulting from this feature, regarded from either aspect, resides in the fact that most of the instrumentalities which go to make up the means for controlling the supply of strips to the rotary carrier do not need to be designed to be carried upon the rotary carrier and, therefore, can be made more rugged, permitting less expensive workmanship. Furthermore, those instrumentalities of the controlling means which do not need to be mounted upon the carrier can be positioned out of the way of the lime dust arising from the usual lime coating upon the strips. This lime dust has a tendency to accumulate on oiled surfaces and impair their lubrication; and an important advantage of this feature of the invention is that it avoids this difficulty.

Another object of the invention is to provide means for positioning the end of the strip which projects rearwardly of the magazine from which the strip is supplied to the presenting means in such manner relatively to the device for transferring the strip to the presenting means as to insure the proper and efficient operation of the transferring device on the strip. In the illustrated construction, the supplying means comprises a plurality of magazines each adapted to contain a single strip, and the magazines are moved successively into alignment with the presenting means and the path of movement of the transferring device. In accordance with this object, a feature of the invention consists in the provisions of means preferably organized

to guide the rear ends of the strips and to dispose the strips in a vertical plane thus preventing them from being bowed downwardly at their ends by the force of gravity.

Another important feature of the invention resides in the provision of means for controlling the nozzle through which the strips are conducted to the cutters or other operating instrumentalities of the machine which will insure the accurate presentation of the strips to the cutters and will, nevertheless, permit the ready discharge of the butt ends of the strips from the machine. Nail making machines commonly comprise a stationary anvil against which the cutters operate to sever the nail blanks from the strip, and, in the preferred embodiment of the invention the controlling means for the nozzle comprises a positioning member disposed to contact with the edge of the strip forwardly of the end of the nozzle and means spaced rearwardly from the end of the nozzle for maintaining the strip against the positioning member, the surface of the stationary anvil being thus left unobstructed at one side thereby permitting the butts of the exhausted strips to pass freely therefrom.

The invention further provides an improved nozzle mechanism which will facilitate the accurate presentation of the strips to the cutters.

Although the invention will be hereinafter described as embodied in mechanism for feeding strips to a nail making machine, it is recognized that in various of its aspects the invention is not limited to such use. Accordingly, the scope of the invention is intended to be limited only as required by the claims.

Still other objects of the invention will appear as the description proceeds and will be pointed out in the appended claims.

In the drawings,

constituting the shifter mechanism for the dog;

Fig. 10 is a view in detail of a guide on the strip carrier;

Fig. 11 illustrates the turret from which the strips are supplied to the strip carrier, the device for transferring the strips to the carrier, and the means for positioning the projecting ends of the strips;

Fig. 12 is a view of the delivery end of the nozzle by which the strips are conducted to the cutters;

Fig. 13 is a view of the same with certain of the parts removed better to exhibit the formation of the end of the nozzle;

Fig. 14 is a cross-sectional view of the nozzle along the line 14—14 of Fig. 12 looking in the direction of the arrows; and

Fig. 15 shows in cross-section the devices for securing the nozzle to the main casting of the strip carrier.

The illustrated machine comprises a frame 2 upon which is mounted a head 4 carrying the mechanism for operating on a nail strip which, as shown, includes cutters 6 and 8 moved downwardly by a cam shaft 10 past the edge of a stationary anvil 12. A stop 14 mounted to move with the cutter 6 determines by its spacing from the edge of the anvil 12 the width of the nail blank severed from the strip.

The nail strip or blank is presented to the cutters 6 and 8 by a tubular carrier 16 the main casting 17 of which is journaled in bearings 18 and 20 of a frame 22 (see Fig. 3) fulcrumed in a yoke-shaped member 24 upstanding from a frame 26. A preferred means for mounting the frame 22 in the yoke 24 comprises studs 28 secured in the yoke by set screws 30 and formed with cone-shaped recesses in their ends adapted to receive the cone-shaped ends of a rod 31 passing through the hub of the frame 22. The frame 22 is slidably adjustable on the rod 31 and may be maintained in any desired position of adjustment thereon by a set screw 32.

The strip carrier 16 is disposed obliquely of the edge of the anvil 12 to the end that the strip may be caused to project further at one of its edges from the anvil than at its other edge so that the blank severed from the strip will taper from one end to the other. It is, of course, necessary to change the relation of the strip to the anvil in order that the blanks severed from the strip subsequently to the first one shall also be tapered. This may be effected in various ways but, in the illustrated construction, the carrier 16 is rotated through an angle of 180° between consecutive operations of the cutters 6 and 8 to present the strip in alternately reversed relations to the cutters by a sprocket chain 33 passing over a sprocket wheel 34 on the carrier 16 and driven from a shaft 36 journaled in the frame 2 of the machine and carrying

an eccentric gear 38 meshing with a like gear on a shaft 40 driven by a chain 42 from the cam shaft 10. A link 43 connected to the frame 22 is operated from the shaft 36 to 5 rock the carrier 16 about the fulcrum studs 28 to elevate the carrier and thereby to permit the carrier to be rotated without interference of the strip with the anvil 12. The arrangement of the eccentric gears is such as to rotate the carrier at relatively slow speed when the strip is lowered on the anvil 12 to facilitate the operation of the cutters 6 and 8 on the strip.

The frame 26 may be adjusted laterally of 15 the head 4 so as to vary the degree of taper of the nail blank severed from the strip. As shown, the frame is joined to the head 4 by links 44 and is provided at its rear end with a tongue slidable in a groove 45 in the up- 20 per end of a supporting standard 46. The groove 45 is curved substantially concentrically with the point of operation of the cutters 6 and 8 on the strip, and the frame 26 may be adjusted in said groove by a screw 47 (see 25 Fig. 11).

The nail strips are fed through the strip carrier 16 by rolls 48 journaled in the casting 17 and rotated intermittently to feed the strip by pawls 49, which are in turn actuated 30 by a stud 50 with which they are moved into engagement by the rotation of the strip carrier. The stud 50 is carried by an arm 52 (Figs. 2 and 3) pivoted in the frame 22 and coacting with an adjustable stop in the form 35 of a set screw or the like 53 to determine variably the extent of the strip feeding movements of the rolls 48. The pawls 49 are moved in the reverse direction by a spring 54 (Fig. 3) preparatory to a subsequent feeding movement. The arm 52 is maintained in 40 the position determined by the stop 53 by a spring 58 (Fig. 4) coiled about the fulcrum of the arm and extended rearwardly of the frame 22 and adapted to engage one of a 45 series of notches (not shown) on the under surface of the hub of the frame whereby the tension of the spring may be adjusted.

Preferably, and in the illustrated construction, the nail strips are supplied one by one 50 to the strip carrier 16 from a turret 60 comprising a plurality of magazines 62 each constructed to receive a single strip. The magazines 62 are disposed parallel to and concentrically of the axis of the turret which 55 is rotated step by step to aline the strips in the magazines successively with the carrier 16 by a Geneva movement designated generally by the numeral 63, Fig. 3, which is driven, through a sprocket chain 64, by a 60 sprocket wheel 65, the hub of which is mounted loosely on a tubular extension 165 (Fig. 6) of the strip carrier 16 and is adapted to be clutched thereto when it is desired to supply a strip to the carrier. The sprocket chain 64 drives a shaft 66 (Figs. 3 and 11)

upon which the driving member of the Geneva movement 63 is mounted and which is extended rearwardly of the turret 60 to actuate mechanism for transferring the strips from the magazines 62 to the carrier 65. As shown, such mechanism comprises a cam 68 on the shaft 66 operable on a roll 70 carried by an arm 72 mounted for swinging movement on a stud 74, the arm 72 having a bent rod 76 extending therefrom and connected at its free end by a link 77 to a transferring device 78 slidable on a bar 79 on the frame 26. The transferring device 78 comprises a palm 80 disposed laterally of the bar 79 in position for engagement with the end of a strip in a magazine alined with the strip carrier 16. The cam 68 moves the transferring device rearwardly on the bar 79 so as to permit the rear end of a strip to pass in front of the palm 80 when the magazine containing the strip is moved into alinement with the strip carrier, such device being moved forwardly to transfer the strip from the magazine to the strip carrier by yielding means which, as shown, comprises a spring 81. It will be understood from the foregoing that when the sprocket wheel 65 is rotated through one revolution, the turret 60 is moved forward far enough to carry one of two adjacent magazines 62 out of and 90 another into alinement with the strip carrier 16 and the transferring device 78 is actuated to transfer the strip in the second magazine to the carrier 16.

Certain of the features of the machine 100 hereinbefore referred to are fully described in the above-mentioned prior Letters Patent, and a more detailed description of such parts of the machine in this application is believed to be unnecessary to a full understanding of 105 the present invention.

In accordance with the invention, the supply of fresh strips to the carrier 16 is effected automatically so as to maintain a continuous supply of strips in the carrier, and the operation of the supplying means is initiated by means on the tubular strip carrier 16 controlled by a strip in the carrier and adapted to actuate controlling means for the clutch connections between the sprocket wheel 65 110 and the carrier 16. As shown, such connections comprise an enlarged portion 82 (Fig. 7) on the hub of the sprocket wheel 65 in which is provided a recess 84 to receive a pin 86 having a finger 88 projecting transversely 115 from its middle portion, the pin being flattened at one side of said finger at 90. The flattened portion of the pin 86 is disposed so as to intersect the path in which a lug 92 on the sprocket wheel 66 moves.

The means for controlling the clutch connections between the carrier 16 and the sprocket wheel 65 comprises a dog 94 and a shifter for the dog which, as shown, includes a shaft 96 upon which the dog is loosely 120

mounted and which is journaled in an extension 98 of the bearing 20 of the frame 22. The hub of the dog 94 is maintained normally against a shouldered surface 100 on a wing 102 forming part of the extension 98 by a spring 103 attached at one of its ends to the wing 102 and at its other end to a lug 104 projecting rearwardly from the hub of the dog 94. Mounted on one end of the shaft 96 is an arm 106 having a boss 108 at its lower end in which is seated a plunger 110 urged upwardly by a spring 112. A pin 113, see Fig. 6, received in a recess of the plunger 110 limits the upward movement of the plunger. Notches 114 and 116 are formed in the lower surface of the dog 94 to receive the edge of the plunger 110, said notches and spring-pressed plunger providing suitable means for movably connecting the dog 94 and the shifter to each other in either of two relative positions. The shifter further comprises a member 118 on the other end of the shaft 96 formed with divaricate arms 120 and 122 each having its end disposed adjacent to the carrier 16. As shown in Fig. 5, the arm 120 is offset somewhat in advance of the arm 122 for a reason that will presently appear. The dog 94 is formed with an arm 124 underlying the hub of the sprocket wheel 65 and disposed to be engaged by the enlarged portion 82 of said hub simultaneously with the engagement of the arm 106 by a second cam portion 126 on said wheel.

The shifter for the dog 94 is actuated by a feeler illustrated as a finger 128 fulcrumed at 130 on the carrier 16 and having one of its ends normally urged towards the path of movement of the strips in the carrier by a spring 131 and its other end 132 projected outwardly from the carrier.

The manner of operation of the mechanism by which the supply of fresh strips to the carrier is initiated and controlled will now be described. Assuming that the finger 128 is in engagement with a strip in the carrier 16, the plunger 110 will be engaged in the notch 116 of the dog 94 which is held against the shoulder 100 of the wing 102 by the spring 103. When the rear end of the strip in the carrier moves past the finger 128, the finger is swung about its pivot 130 outwardly and forwardly by the spring 131 to a position such that upon continued rotation of the carrier the end 132 of the finger impinges upon the end of the arm 120 and through the connection between the plunger 110 and the dog 94 moves the dog from beneath the finger 88. So long as the finger 88 is upheld by the dog 94, the flattened portion 60 of the pin 86 is so disposed relatively to the lug 92 that the lug will pass by said pin during the rotations of the gear 34 without engaging the pin. Upon the withdrawal of the dog 94 from beneath the finger 88, however, the pin 86 upon the force of gravity

acting on the finger 88 is turned so as to dispose the flattened end of the pin across the path of movement of the lug 92, so that continued rotation of the gear wheel 34 will cause rotation of the gear wheel 65.

If the gear wheel 65 were to be continuously rotated, a number of strips would be forced into the strip carrier which is designed to receive but one strip at a time. The introduction of more than a single strip into the carrier upon the initiation of the operation of the strip supplying means is, in the operation of the illustrated construction, prevented by movement of the arm 106 outwardly by the cam 126 while the dog 94 is withheld from movement by the action of the enlarged portion 82 of the wheel on the arm 124 of the dog. Such movement of the arm 106 carries the arm 120 away from the carrier 16 and out of the path of movement of the end 132 of the finger 128, the plunger 110 being at the same time moved from the notch 116 to the notch 114. While the plunger 110 engages notch 114 the arm 106, together with the arm 120 which is rigidly connected thereto through shaft 96, is held in such relation to the dog 94 that when cam portion 126 passes away from arm 106 arm 120 is held out of the path of movement of the end 132 of finger 128, and this in spite of the fact that dog 94 is held by spring 103 in the path of movement of finger 88. Thus looking at the parts from the direction in which they are viewed in Fig. 6, and assuming them to be with dog 94 held by spring 103 in the position there shown, when the plunger 110 is moved from the position there shown to the position in which it engages notch 114, arms 106 and 120 move counter-clockwise to such an extent that the extremity of arm 120 is no longer in the path of movement of the end 132 of finger 128. It will be understood that the dog 94 is returned into the path of movement of the finger 88 by the spring 103 immediately after the finger 128 passes out of contact with the end of the arm 120. Accordingly, when the gear wheel 65 has completed a single revolution, the finger 88 on the pin 86 will be again engaged by dog 94, inasmuch as the arm 120 is no longer in position to be actuated by the finger 128, and will turn the pin to unclutch the gear wheel 65 from the gear wheel 34. With this construction, only a single operation of the supplying means designed to supply a single strip to the carrier is effected whether a strip is actually supplied to the carrier or not, and repeated useless operation of the supplying means will be avoided.

When a fresh strip is introduced into the carrier, it pushes back the inner end of the finger 128, thereby positioning the end 132 of the finger inwardly and rearwardly so as to wipe upon the upper surface of the arm

122. Since the dog 94 abuts against the shoulder 100 of the wing 102 and is thus precluded from movement with the shifter, the wiping of the end 132 of the finger 128 on the arm 122 moves the shifter relatively to the dog so as to carry the plunger 110 from the notch 114 back into the notch 116 thus resetting the clutch controlling means. This completes the cycle of operations, the end 132 of the finger 128 being then maintained out of operative relation to the arm 120 against the tension of the spring 131 by the strip until the rear end of the strip passes from engagement with the finger 128 after which the finger will again actuate the arm 120 to initiate the supply of another strip to the carrier. The above-mentioned offset between the arms 120 and 122 enables these arms to be engaged by the end 132 in its forward and rearward positions respectively.

In order effectively to control the strip in its passage through the carrier and to position it accurately with relation to the feed rolls 48, a strip guide 134 is secured to the main casting 17 of the carrier rearwardly of the feed rolls, the term rearward being employed to denote that direction which is opposite to the direction of feed of the strip. Preferably and, as shown (see Fig. 10) such guide comprises a sheet metal plate formed with a rearwardly extending ear 136 secured to the casting 17 by a set screw or the like 137 (Fig. 3) and recessed at its under side to receive the strip. Wings 138 and 140 are provided on the plate for yielding engagement with the edges of the strip in the carrier, said wings being preferably constituted by integral portions of the plate bent laterally to form the recess for the strip. A third flexible wing 142 is carried by the plate for contact with a side of the strip. The wings 138, 140, and 142 extend from the plate toward the feed rolls 48 and their ends engage the strip adjacent to the point of operation of the feed rolls on the strip.

It has been found in the use of machines of the type of the illustrated machine that the rear ends of the strips when allowed to hang free from the magazines are frequently not properly positioned relatively to the palm 80 of the transferring device 78 when the magazines containing them are moved into alignment with the strip carrier. For example, the end of the strip in the aligned magazine is sometimes bowed downwardly by the force of gravity to an extent such that the palm 80 does not engage the extremity of the strip but is carried against its side so that the palm is caused to bend the strip at the end of the magazine instead of pushing it forwardly into the strip carrier. In order to insure the proper positioning of the end of the strip for operation thereon by the palm 80, I have provided the following mechanism (see Fig. 11). A bracket 144 on the frame

26 is formed with an upper arm 146 and a lower arm 148. The arm 148 has secured thereto preferably by being formed integral with the upper arm 146 a track 150 having one of its ends disposed substantially in the horizontal plane of the lowermost point of the path of movement of the magazines and extending laterally of the path of movement of the ends of the strips in the magazines by a distance such as to preclude the possibility of a strip passing beneath the track. The other end of the track 150 is curved upwardly and has spaced above it a correspondingly curved member 152 carried by the upper arm 146. Secured to the members 150 and 152 by blocks 153 and 154 clamped upon them by set screws 155 and 156 are flat curved spring members 158 and 160 respectively. The members 150 and 153 and their flexible extensions 158 and 160 guide the rear ends of the strips and support them during part of their movement to the transferring device 78. The extensions 158 and 160 extend upwardly across the path of movement of the transferring device 78 and inasmuch as they are spaced from each other by a distance substantially equal to the thickness of a strip, they maintain the strips in a vertical plane. Being flexible, the members 158 and 160 yield readily to permit the movements of the transferring member. It will be understood that a strip disposed in a horizontal plane in one of the magazines 62 may bow downwardly considerably at its end since it will flex readily on its lower side. When, however, the strip is disposed in the magazine in a vertical plane with an edge of the strip on its lower side, it will not flex to any appreciable extent.

When the turret is recharged, the ends of the strips in the magazines at the upper part of the turret are liable to be bent down far enough to be engaged by the palm 80 of the transferring device. To prevent this, I provide means for supporting the ends of such strips which, in the illustrated construction, is exemplified by a bent rod 162 extending upwardly from the arm 146 and being formed with the downwardly and upwardly inclined portions 163 and 164 forming a saddle in which the strips rest.

The strip carrier 16 is provided with a nozzle 166 received in a passage 167 (Fig. 4) of the main casting 17 of the carrier and held in place in the casting by suitable means which, as shown, includes a latch 267 (Fig. 15) having a reduced end fitting into an opening in the nozzle and normally maintained in locking engagement with the nozzle by a spring 168 received in a bore of the latch 267 and operating against a pin 268 passing through an opening in the latch large enough to permit it to be moved against the resistance of the spring 168 to release the nozzle. A pin or the like (not shown) on the nozzle 166 is received in a slot 269 of the main casting 17.

17 of the strip carrier (see Fig. 2) and thus limits the lateral movements of the nozzle about the latch 267. An inverted U-shaped leaf spring 169 secured to the head of the machine by a block 270 engages the nozzle 166 at a point remote from the delivery end of the nozzle and insures the proper positioning of the strip for operation thereon by the cutters 6 and 8 by urging the edges of the strip against the positioning member 271 (see Fig. 2) as the strip is turned by the carrier 16. It is impossible to convert the strips into nails in their entirety, inasmuch as they cannot be controlled by the nozzle so as to present them to the cutters when they are nearly used up. In the operation of nail making machines as heretofore constructed, considerable difficulty has been experienced in discharging the butt ends of the strips from the machine, so that they frequently accumulated on the fixed anvil where they interfered seriously with the operation of the nozzle and the cutters. Such difficulty is, however, avoided by the present construction, since thereby the upper surface of the stationary anvil 12 is left unobstructed at one side, as will clearly appear from Fig. 2, from which it will be seen that the butts may pass readily from the left side of the anvil 12.

The invention further aims to improve the construction of the nozzle so as better to present the strips to the cutters. To this end, there are fulcrumed to the nozzle 166 by bolts 170 and 171 respectively, members 172 and 174 having their ends 176 and 178 extending beyond the delivery end of the nozzle 166 and being grooved to receive the marginal portions of the strip. Said members are U-shaped in cross-section so as to embrace the edges of the nozzle 166 and their sides are bent inwardly intermediate between their main body portions and their grooved end portions over the shoulders formed at each side of the delivery end of the nozzle by the reduced extension 367 thereof. Leaf springs 180 and 182 secured to the sides of the nozzle by the bolts 170 and 171 extend outwardly from the end of the nozzle to substantially the same extent as the members 172 and 174 and are adapted for engagement with the sides of the strip. The grooved ends 176 and 178 of the members 172 and 174 are maintained against the edges of the strip in the nozzle by plates 184 and 186 slidably adjustable on the nozzle and secured in any desired position of adjustment thereon by bolts 188 and 190 passing through elongated slots in the plates. As shown, the members 172 and 174 are bent outwardly at their rear ends 192 and 194 away from the sides of the nozzle 166, thus presenting inner surfaces diverging from the sides of the nozzle against which the plates 184 and 186 operate. The plate 186 has formed thereon an extension 196 bowed outwardly at 198 for engagement

with the end 194 of the member 174, and the plate 184 has an extension 200 bowed outwardly at 202 for engagement with the end 192 of the member 172. The end of the extension 196 contacts with the side of the nozzle 166 and thus maintains the grooved end 178 of the member 174 positively against outward movement. The extension 200, however, is spaced at its end from the side of the nozzle 166 in order to permit the grooved end 176 of said member to yield outwardly when required to accommodate itself to the strip. To facilitate the flexure of the extension 200, it is continued into the body of the plate 184 by the formation of a slot 204 in the plate. The plate 184 is formed with a flange 206 fitted into a slot 208 in the nozzle 166 in order to assure a firm support for the plate. The maintenance of the member 174 in fixed position enables the strips to be presented invariably in the same relation to the cutters 6 and 8, whereas if both of said members were yieldingly mounted, both might be simultaneously moved in the same direction from their normal positions thus causing the strip to be improperly positioned relatively to the cutters. The normal positions of the grooved ends 176 and 178 of the members 172 and 174 may be suited to the width of the strip being operated upon by adjusting the plates 184 and 186.

Having fully described my invention, what I claim as new and desire to secure by Letters Patent of the United States is:—

1. In a nail making machine, means for operating on a nail strip, a rotary carrier for presenting a strip to said operating means, means for supplying strips to said carrier, mechanism for controlling said supplying means, a support for said controlling mechanism relatively to which support the carrier rotates, and a feeler mounted on said carrier and arranged to occupy either of two positions dependent upon the presence or absence of a strip, said controlling mechanism being constructed and arranged upon engagement with said feeler in one of said positions of said feeler to cause said supplying means to supply a strip to said carrier.

2. In a nail making machine, means for operating on a nail strip, a rotary carrier for presenting a strip to said operating means, means for supplying strips to said carrier, mechanism for controlling said supplying means, a support for said controlling mechanism relatively to which support the carrier rotates, and a feeler mounted on said carrier and arranged to occupy either of two positions dependent upon the presence or absence of a strip, said controlling mechanism being constructed and arranged upon engagement with said feeler in one of said positions of said feeler to cause said supplying means to supply a strip to said carrier and when engaged by said feeler in the other of said posi-

tions of said feeler to be reset for further operation.

3. In a nail making machine, means for operating on a nail strip, a rotary carrier for presenting a strip to said operating means, means for supplying strips to said carrier, mechanism for controlling said supplying means, a support for said controlling mechanism relatively to which support the carrier rotates, a feeler mounted on said carrier and arranged to occupy either of two positions dependent upon the presence or absence of a strip, said controlling mechanism being constructed and arranged upon engagement with said feeler in one of said positions of said feeler to cause said supplying means to supply a strip to said carrier, and means for rendering said controlling means inoperative to avoid further actuation of said supplying means.

4. In a nail making machine, means for operating on a nail strip, a rotary carrier for presenting a strip to said operating means, means for supplying strips to said carrier, mechanism for controlling said supplying means, a support for said controlling mechanism, relatively to which support the carrier rotates, a feeler mounted on said carrier and arranged to occupy either of two positions dependent upon the presence or absence of a strip, said controlling mechanism being constructed and arranged upon engagement with said feeler in one of said positions of said feeler to cause said supplying means to supply a strip to said carrier, and means for rendering said controlling means inoperative to avoid further actuation of said supplying means, said controlling mechanism being also constructed and arranged upon engagement with said feeler in the other of said positions of said feeler to be restored to operative condition.

5. In a nail making machine, means for operating on a nail strip, means for presenting a strip to the operating means, means for supplying strips to the presenting means, controlling means for the supplying means comprising arms disposed with their ends adjacent to the presenting means, and a member mounted on the presenting means for engagement with the strip and adapted to occupy either of two positions, in one of which said member upon operation of the presenting means is moved into engagement with one of said arms to render the supplying means operative and in the other of which said member is adapted to engage the other of said arms to reset the controlling mechanism for further operation of the supplying means.

6. In a nail making machine, means for operating on a nail strip, means for presenting a strip to the operating means, means for supplying strips to the presenting means, means for controlling the operation of the

supplying means comprising a device normally positioned to render the supplying means inoperative, means carried by the presenting means for moving said device to a position to render the supplying means operative, and means movable with the supplying means for operatively disconnecting the controlling means from the presenting means.

7. In a nail making machine, means for operating on a nail strip, means for presenting a strip to the operating means, means for supplying strips to the presenting means, means for controlling the operation of the supplying means comprising a member normally positioned to render the supplying means inoperative, a shifter movably connected with said member, means carried by the presenting means and operable on said shifter to move said member from its normal position to render the supplying means operative, and means movable with the supplying means for effecting relative movement of said shifter and said member to render the presenting means inoperative on said member.

8. In a nail making machine, means for operating on a nail strip, means for presenting a strip to the operating means, means for supplying strips to the presenting means, means for controlling the operation of the supplying means comprising a member positioned normally to render the supplying means inoperative, a shifter connected to said member and movable relatively thereto, a member carried by the presenting means and operable on said shifter in one position of the shifter relatively to the controlling member to move said member to a position to render the supplying means operative, and cam mechanism operatively connected to the supplying means for moving said shifter relatively to the controlling member out of operative relation to the presenting means.

9. In a nail making machine, means for operating on a nail strip, means for presenting a strip to the operating means, means for supplying strips to the presenting means, controlling means for the supplying means constructed and arranged when actuated to cause the supply of a single strip to the presenting means, mechanism on the presenting means for engagement with an element of the controlling means for actuating the controlling means upon the passage of the rear end of a strip past said mechanism, means associated with the supplying means for rendering said actuating mechanism inoperative on said element after a single operation of the supplying means, and a part on said controlling means operable by said mechanism upon the supply of a fresh strip to the presenting means to restore the operative relation between the element and said mechanism.

10. In a nail making machine, means for

- operating on a nail strip, means for presenting a strip to the operating means, means for supplying strips to the presenting means, a device for rendering the supplying means normally inoperative, a shifter for said device movable relatively to said device, a member carried by the presenting means and controlled by the strip so as to occupy either of two positions, said member being movable upon the passage of the rear end of a strip in the presenting means thereby to a position to actuate the shifter to move said device out of operative relation to the supplying means to render the supplying means operative, means movable with the supplying means and operable on said shifter to move the shifter relatively to said device out of operative relation to the actuating member when in its first-mentioned position, and means carried by the shifter and operable by the actuating member when moved to a second position by the supply of a fresh strip to the presenting means to move the shifter back into operative relation to the actuating member.
11. In a nail making machine, means for operating on a nail strip, means for presenting a strip to the operating means, a magazine adapted to contain a single strip with the end of the strip projecting from the magazine, means for transferring the strip endwise from the magazine to the presenting means, and means for positioning the projecting end of the strip relatively to the transferring means constructed and arranged to dispose the strip laterally in a vertical plane in the magazine so as to prevent bowing of the strip by gravity.
12. In a nail making machine, means for operating on a nail strip, means for presenting a strip to the operating means, a magazine constructed and arranged to contain a single strip with the end of the strip projecting rearwardly from the magazine, means for transferring the strip from the magazine to the presenting means, means for moving the magazine into endwise alinement with the presenting means and the transferring means, and means spaced from the magazine and operable on the rear end of the strip to position the strip laterally in a vertical plane in the magazine at the point of operation thereon by the transferring means, said positioning means comprising members spaced from each other and adapted to receive the strip between them.
13. In a nail making machine, means for operating on a nail strip, means for presenting a strip to the operating means, a magazine constructed and arranged to contain a single strip with the end of the strip projecting rearwardly from the magazine, means for transferring the strip from the magazine to the presenting means, means for moving the magazine into endwise alinement with the presenting means, and means spaced from the
- magazine and operable on the rear end of the strip to dispose the strip laterally in a vertical plane in the magazine at the point of operation thereon by the transferring means, said means comprising spaced flexible members constructed to form a guideway for the strip and extending into the path of movement of the transferring means.
14. In a machine of the class described, means for operating on a nail strip, means for presenting a strip to the operating means, means disposed forwardly of the presenting means for positioning the strip relatively to the operating means, and means operable on the presenting means for moving the strip laterally against the positioning means.
15. In a machine of the class described, means for operating on a nail strip, means for presenting a strip to the operating means, positioning means for the nail strip formed to present a strip engaging surface in advance of the presenting means, and means operable on the presenting means for pressing an edge of the strip against said surface.
16. In a machine of the class described, means for operating on a nail strip, means for presenting a strip to the operating means, guiding means for the nail strip disposed forwardly of the end of the presenting means formed to present a guiding surface for engagement with the edge of the strip, yielding means operable on the presenting means tending normally to maintain an edge of the strip in contact with said guiding surface, and means for operating the presenting means to move the opposite edges of the strip alternately into engagement with the guiding surface.
17. In a machine of the class described, means for operating on a nail strip, means for presenting a nail strip to the operating means comprising a carrier including a nozzle fulcrumed in the carrier, means for turning the carrier about its axis to present the strip in alternately reversed relations to the operating means, positioning means for the strip disposed forwardly of the delivery end of the nozzle, and means operable on the nozzle for causing the edges of the strip to engage said positioning means.
18. In a machine of the class described, means for operating on a nail strip, means for presenting a nail strip to the operating means comprising a carrier and a nozzle fulcrumed in the carrier, means for turning the carrier about its axis to present the strip in alternately reversed relation to the operating means, and means for positioning the strips relatively to the operating means comprising mechanism operable on said nozzle, said means being constructed and arranged to permit the discharge of the stub ends of the strips from the field of operation of the operating means.
19. In a machine of the class described,

means for operating on a nail strip comprising a stationary anvil having an upper surface on which the strip is disposed, means for presenting the nail strip to the operating means comprising a carrier and a nozzle fulcrumed in the carrier, means for turning the carrier about its axis to present the strip in alternately reversed relations to the operating means, and means for positioning the strip relatively to the operating means comprising mechanism operable on the nozzle and constructed and arranged to leave the upper surface of the anvil unobstructed at one side thereby to permit the ready discharge of the stub ends of the strip from the anvil out of the field of operation of the operating means.

20. In a machine of the class described, the combination with means for operating on a nail strip comprising a stationary anvil having an upper surface on which the strip is disposed, means for presenting strips to the operating means comprising a carrier and a nozzle fulcrumed in the carrier, means for turning the carrier about its axis to present the nail strip in alternately reversed relations to the operating means, and means for insuring the accurate positioning of the strip relatively to the operating means comprising a member formed to present a guiding surface disposed forwardly of the end of the nozzle, and means spaced from the delivery end of the nozzle and operable on the nozzle to thrust the edges of the strip into contact with said guiding surface.

21. In a nail making machine, the combination with a nozzle slotted to receive a strip, of members mounted on the nozzle adjacent to its delivery end and provided with grooved ends extending beyond the end of the nozzle and adapted to receive the marginal portions of the strip, and means adjustable to accommodate strips of varying widths for resisting outward movement of the grooved ends of said members.

22. In a nail making machine, the combination of a nozzle having a slot to receive a nail strip, members fulcrumed on the nozzle adjacent to its delivery end and provided with grooved ends adapted to receive the marginal portions of the strip, and means adjustably mounted on the nozzle rearwardly of the fulcrum points of said members for maintaining the grooved ends of said members pressed inwardly against the marginal portions of the strip.

23. In a nail making machine, the combination of a nozzle having a slot to receive a nail strip, members fulcrumed on the nozzle adjacent to its delivery end and having grooved end portions extending beyond the delivery end of the nozzle constructed to receive the marginal portions of the strip, and separate means carried by the nozzle for maintaining said members against the edges of the strip,

one of said means being constructed to permit the corresponding member to yield to accommodate strips of varying widths.

24. In a nail making machine, the combination of a nozzle having a slot to receive a nail strip, members fulcrumed on the nozzle adjacent to its delivery end and having grooved end portions extending beyond the delivery end of the nozzle to receive the marginal portions of the strip, and having portions at their rear ends inclined outwardly from the sides of the nozzle, and devices carried by the nozzle to the rear of said members and operable against the inclined portions of said members to maintain the grooved end portions of said members inwardly against the edges of the strip.

25. In a nail making machine, the combination of a nozzle having a slot to receive a nail strip, members fulcrumed on the nozzle adjacent to its delivery end and having grooved end portions extending beyond the delivery end of the nozzle to receive the marginal portions of the strip and having portions at their rear ends inclined outwardly from the sides of the nozzle, and devices independently adjustable on the nozzle and comprising outwardly bowed portions for engagement with the inclined portions of said members to maintain the grooved end portions of said members inwardly against the edges of the strip.

26. In a nail making machine, the combination of a nozzle having a slot to receive a nail strip, members fulcrumed on the nozzle adjacent to its delivery end and having grooved end portions extending beyond the delivery end of the nozzle to receive the marginal portions of a strip, said members having portions at their rear ends inclined outwardly from the sides of the nozzle, and devices carried by the nozzle and comprising portions bowed outwardly from the nozzle for engagement with the inclined portions of said members to maintain the grooved ends of said members inwardly against the edges of the strip, one of said bowed members being spaced at its end from the side of the nozzle so as to yield to permit movement of the corresponding member to accommodate itself to strips of varying widths.

27. In a nail making machine, the combination of a nozzle, and means for controlling the end of a strip in the nozzle comprising a member having a grooved end portion extending beyond the delivery end of the nozzle to receive the marginal portion of a strip and formed to present a surface inclined outwardly from the side of the nozzle, and a device having a bowed portion for engagement with said outwardly inclined surface and spaced at its end from the nozzle so as to yield to permit outward movement of the grooved end of said member.

28. In a nail making machine, the combination of a nozzle and means for controlling the

end of a strip in the nozzle comprising a member having a grooved end portion extending beyond the delivery end of the nozzle to receive the marginal portion of a strip, and a device for maintaining the grooved end of said member inwardly against the edge of the strip comprising a plate slidably mounted on the nozzle and having a portion for engagement with said member separated from the body of the plate by a slot extending inwardly from the edge of the plate and spaced at its end from the side of the nozzle to permit outward movement of the grooved end of said member.

15 In testimony whereof I have signed my name to this specification.

GEORGE GODDU.
